Primary Examiner — Robert M Spear*Assistant Examiner* — Rashida C McCoy(74) *Attorney, Agent, or Firm* — Fish & Richardson P.C.(57) **CLAIM**

The ornamental design for a connector for constructional materials, as shown and described.

DESCRIPTION

FIG. 1 is a perspective view of a connector for constructional materials showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof, the left side view being a mirror image of FIG. 6;

FIG. 7 is a cross-sectional view taken along line 7-7 in FIG. 2; and,

FIG. 8 is a referential view showing the article in use. The features shown in broken lines in FIG. 8 depict environmental subject matter only and form no part of the claimed design.
